HOIST

Michael Cullum Nesbitt, Victoria, British
Columbia, Canada

Application June 23, 1937, Serial No. 149,974

13 Claims. (Cl. 254—185)

This invention relates to a hoist which may be used for any purpose.

An object of the present invention is the provision of a hoist which may be operated without loss of power.

Another object is the provision of a hoist having only a single source of power.

Another object is the provision of a portable hoist which may be set up as a complete, compact unit.

A further object is the provision of a portable hoist which may be used as an ordinary single or two drum hoist or for skidder rigging or for counterbalancing buckets running to different stations in a shaft or for many other purposes.

A still further object is the provision of a portable hoist of comparatively simple construction and which may be very easily operated.

There are various types of hoists now in use with differential couplings but most of these are so cumbersome that they cannot be set up as a single, portable unit. Another disadvantage of the present hoists is that most of them require more than one source of power and that they necessarily must operate a great deal of the time against their brakes resulting in a great loss of power.

The present invention provides a hoist having a single source of power which may be directly connected to either or both the drums and which may also be connected to said drums through a differential whereby the drums may be held in constant relation or when one drum is braked the other may be wound or unwound as desired. With this hoist there is no waste of power since it is so constructed that the drums do not rotate against the drag of a brake when one drum is pulling the cable off the other. The drums, the differential and the source of power may be conveniently mounted on a sled or truck for transportation.

This invention consists essentially of a pair of independently mounted drums selectively connected to each other and to a source of power by gears. These drums are also independently connected to the source of power through a differential. There is a clutch for disconnecting the differential from the source of power and a brake on the shaft leading to said differential by means of which the latter may be held stationary. The differential is mounted beneath the drums and the source of power is mounted behind the drums so that the hoist is a complete, compact unit which may be very easily moved from place to place as more fully de-

scribed in the following specification and illustrated in the accompanying drawings, in which

Figure 1 is a side elevation of the hoist with the side frame removed,

Figure 2 is a plan view of the hoist,

Figure 3 is an elevation of the side of the hoist opposite that shown in Figure 1 with certain parts broken away,

Figure 4 is a vertical section taken on the line 4—4 of Figure 3,

Figure 5 is a fragmentary plan view of the hoist with one of the cable drums removed,

Figure 6 diagrammatically illustrates one use for the hoist,

Figure 7 diagrammatically illustrates another use for the hoist, and

Figure 8 diagrammatically illustrates still another use for the hoist.

Referring more particularly to the drawings, 10 is a base having side frames 11 and 12 adapted to support the drums and their operating gears. A cable drum 13 is freely and slidably mounted on a shaft 14 journalled in bearings 15 formed on the side frames 11 and 12 and a cable drum 16 is freely and slidably mounted on a shaft 17 journalled in bearings 18 formed on said side frames. The drum 13 is provided at one end with a spur gear 20 and at its other end with a brake drum 21 engaged by a brake band 22 one end of which is anchored to an arm 24 supported by the frame 12 and the other end of the band is connected to a cam 25 secured to a brake rod 26 having an operating pedal 27. The drum 16 is provided at one end with a spur gear 28 substantially opposite the brake drum 21 of the drum 13 and at its other end with a brake drum 30 engaged by a brake band 31 one end of which is anchored at 32, the other end of said band being connected to a cam 33 secured to a brake rod 34 having an operating pedal 35.

A spur gear 36 is fixedly mounted on the shaft 14 adjacent the brake drum 21 of the drum 13 and is provided with a friction cone 37 adapted to extend into a conical recess 38 in the brake drum. Any suitable clutch mechanism such as diagrammatically illustrated at 40 is mounted on the opposite end of the shaft 14 and is adapted selectively to thrust the drum 13 into engagement with the friction cone 37, said clutch mechanism being operated by a handle 41. Similarly, a spur gear 42 is fixedly mounted on the shaft 17 adjacent the spur gear 28 of the drum 16 and is provided with a friction cone 43 adapted to extend into a conical recess 44 formed within the gear 28. Any suitable clutch mechanism 55

such as diagrammatically illustrated at 45, is mounted on the opposite end of the shaft 17 and is adapted selectively to thrust the drum 16 into engagement with the friction cone 43, said clutch mechanism being operated by a handle 46.

A differential generally designated by the numeral 47, is mounted centrally of the base 19 beneath the drum 13 in a suitable mounting 48. The differential 47 comprises a housing 50 having 10 hollow, cylindrical extensions 51 extending outwardly therefrom, said extensions being journaled in bearings 52 formed on the mounting 48. The housing 50 has mounted therein two or 15 more spider gears 53 adapted to mesh with bevel gears 54 and 55 fixedly secured to the inner ends of shafts 56 and 57 respectively. Said shafts 56 and 57 extend outwardly through the hollow extensions 51 and their outer ends are journaled in bearings 58 and 60 formed on the side frames 20 11 and 12. A crown gear 61, mounted on one of the extensions 51 at one side of the housing 50, is secured to said housing and is adapted to mesh with a pinion gear 62 fixed to the inner end of a differential drive shaft 63 which is journaled in 25 a bearing 64 formed on the mounting 48. The shaft 63 extends rearwardly to a transmission box 65 and has mounted thereon a brake drum 66 engaged by a brake band 67 one end of which is anchored at 68, the other end of said band 30 being connected to a cam 69 secured to a brake rod 70. A lever 71 is secured at its inner end to the brake rod 70, said lever extending outwardly from the brake rod through the side frame of the hoist.

35 A gear 75, fixed to the shaft 56, is adapted to mesh with the spur gear 20 of the drum 13 and a gear 76, fixed to the shaft 57 is adapted to mesh with the spur gear 28 of the drum 16. A gear 77, freely mounted on the shaft 57 outside the gear 76, is adapted to mesh with both 40 of the spur gears 36 and 42.

A pinion gear 78, fixed to a stub shaft 80, meshes with the spur gear 36. The stub shaft 80 is journaled in an arm 81 and a bracket 82 45 spaced therefrom, said arm and said bracket being mounted on and extending outwardly from the rearward end of the side frame 12. A sprocket 83 is mounted on the stub shaft 80 between the arm 81 and the bracket 82 and is connected by 50 a chain 84 to another sprocket 85 mounted on the front end of a power shaft 86 of a suitable source of power of any type, such as a Diesel engine 87, mounted on the rearward end of the base 10. It is to be understood, however that the pinion gear 78 may be connected to the power shaft 86 in any other suitable manner, such as by 55 means of a clutch and variable gears of any standard type. The rearward end of the power shaft 86 extends into the transmission box 65 and is connected to the differential drive shaft 63 by a suitable clutch and variable gearing, not 60 shown, which may be engaged or disengaged by an operating lever 88. For example, a sleeve 92 may be slidably mounted on the shaft 86 within 65 the box 65, said sleeve having spaced bevel gears 93 and 94 adapted to be moved into and out of engagement with a bevel gear 95 mounted on the shaft 63 within said box. The sleeve 92 may be moved along the shaft 86 by means of the operating lever 88 which is connected to said sleeve 70 by a yoke 96. The sleeve may be moved so that either one or neither of the gears 93 and 94 mesh with the gear 95. The sleeve 92 extends into the hollow fly wheel 97 of the engine 87 and has a clutch plate 98 mounted thereon within said fly 75

wheel. When both the gears 93 and 94 are out of engagement with the gear 95, the clutch plate 98 does not engage either inner surface of the fly wheel but when the lever 88 is moved in one direction, one of the gears, say gear 93, for example, meshes with the gear 95 and, as the lever continues to move, the clutch plate engages an inner surface of the fly wheel. Practically the same thing happens when the lever 88 is moved in the opposite direction to bring the gear 94 into 10 engagement with the gear 95, the only difference being that the clutch plate engages the opposite inner surface of the fly wheel.

Cables 90 and 91, secured at their inner ends to the drums 13 and 16 respectively, are adapted 15 to be wound or unwound from their respective drums.

In operation, the pinion gear 78 is turned to the right in Figure 1 and to the left in Figure 3 by the engine 87. The spur gears 36 and 42 normally turn over idly since the gear 36 meshes with the pinion gear 78 and the gear 42 meshes with the gear 77 which in turn meshes with the gear 36. When it is desired to reel in the cable 90 on to drum 13, said drum is thrust over into 20 engagement with the friction cone 37 by means of the handle 41 and its associated clutch mechanism. This causes the drum to rotate with the spur gear 36. Similarly, the cable 91 may be reeled on to the drum 16 by thrusting said drum 25 into engagement with the friction cone 43 by the handle 46 and its associated clutch mechanism which movement causes the drum to rotate with the spur gear 42.

The drum 13 will reel in and the drum 16 will 30 unreel when the friction cone 37 engages the drum 13 and the friction cone 43 is disengaged from the drum 16 with the differential drive shaft 63 disengaged from the engine 87 and held stationary by the brake band 67. As the drum 13 35 turns with the spur gear 36 and reels in, the spur gear 20 rotates the gear 75, the shaft 56 and the bevel gear 54. Since the housing 50 is stationary, the bevel gear 54 rotates the bevel gear 55 in the opposite direction through the spider gears 53. 40 The gear 55 rotates the shaft 57, gear 76 and the spur gear 28 causing the drum 16 to unreel. By reversing this procedure, the drum 13 may 45 be made to unreel and the drum 16 reel in. In this case the friction cone 37 is disengaged from the drum 13 and the friction cone 43 engages the drum 16 to cause it to reel in. As the drum 16 50 reels in, the spur gear 28 rotates the gear 76, shaft 57 and the bevel gear 55. Since the housing 50 is stationary, the bevel gear 55 rotates the bevel gear 54 in the opposite direction through the spider gears 53. The bevel gear 54 rotates the shaft 56, the gear 75 and the spur gear 20 55 which causes the drum 13 to unreel.

When the differential drive shaft 63 is held 60 stationary, as described above, if the drum 13 is forced to unreel by a pull on cable 90, the motion will be transferred through the differential causing drum 16 to reel in the cable 91. Similarly, when the drum 16 is forced to unreel by a pull 65 on cable 91, the drum 13 will reel in. In other words, when the differential brake is on, the cables 90 and 91 are counterbalanced against each other through the differential.

If the friction cones 37 and 43 are disengaged 70 from their respective drums and the differential drive shaft 63 engaged with the engine with the drum 13 braked, the drum 16 will reel in. The housing 50 rotates but the bevel gear 54 is held 75 stationary due to the braking of the drum 13. 75

The spider gears 53 rotate the bevel gear 55 in the same direction as the housing 50. The bevel gear 55 rotates the shaft 57, gear 76 and the spur gear 28 which causes the drum 16 to reel in. Similarly if the friction cones 37 and 43 are disengaged from their drums and the differential engaged with the engine with the drum 16 braked, the drum 13 will reel in. The housing 50 rotates but the bevel gear 55 is held stationary due to the braking of drum 16. The spider gears 53 rotate the bevel gear 54 in the same direction as the housing 50. The bevel gear 54 rotates the shaft 56, gear 75 and the spur gear 20 which causes the drum 13 to reel in.

If both the brakes 22 and 31 are off and the differential drive shaft engaged with the engine, either or both the drums 13 and 16 will reel in depending on the pulls on the cables 90 and 91 since the pull on either one of the cables may be the equivalent to braking its drum. In fact, the pull on one cable might be sufficient to reel out one drum causing the other drum to reel in more quickly. In this case, the total amount of cable out would be reduced as long as the differential drive was engaged. If the differential drive shaft 63 is disengaged from the engine and the brake 67 is off, either of the drums could be reeled in or unreel independently of the other, as the relative motion would only result in the rotation of the shaft 63.

If it is desired to unreel either or both the drums by power it would be necessary only to incorporate a reverse gear system in the transmission box 65 so that the above described differential actions would be reversed. For example, with a reverse gear system in the transmission box 65, the differential shaft 63 could be made to rotate in a direction opposite to that shown by the arrow in Fig. 1. In this case, if the friction cones 37 and 43 are disengaged from their respective drums and the differential drive shaft 63 engaged with the engine with the drum 13 braked, the drum 16 will unreel. The housing 50 rotates in the opposite direction to that previously described and the bevel gear 54 is held stationary due to the braking of the drum 13. The spider gears 53 rotate the bevel gear 55 in the same direction as the housing 50. The bevel gear 55 rotates the shaft 57, gear 76 and the spur gear 28 which causes the drum 16 to unreel. Similarly, in this example, if the friction cones 37 and 43 are disengaged from their drums and the differential engaged with the engine with the drum 16 braked, the drum 13 will unreel. The housing 50 rotates in the reverse direction and the bevel gear 55 is held stationary due to the braking of the drum 16. The spider gears 53 rotate the bevel gear 54 in the same direction as the housing 50. The bevel gear 54 rotates the shaft 56, gear 75 and the spur gear 20 which causes the drum 13 to unreel. Also, if the brakes 22 and 31 are off and the differential drive shaft engaged, as in this example, either or both the drums 13 and 16 will unreel depending on the pulls on the cables 90 and 91. If the load on these cables is approximately equal, both drums will unreel while, if the load on one cable is greater than that of the other cable, the first cable will unreel faster than the second one.

When the load on the cables is equal, the both of the bevel gears 54 and 55 are locked with and rotate in the same direction as the housing 50 so that the gears 75 and 76 also rotate in the same direction to unreel the drums 13 and 16 through the spur gears 20 and 28.

Any number of cable drums may be used with this hoist. The additional drums would be connected to the source of power through the gears 42, 77, 36 and 78.

Figures 6, 7 and 8 illustrate, as examples, three ways in which this hoist may be employed. Figure 6 shows a method of picking up a load and moving it from one spot to another. A sky line 94 extends from one support 95 to another support 96 and a trolley 97 is adapted to be moved back and forth along said sky line. The cable 90 extends outwardly from the drum 13, through a lead block 98 mounted on the support 96, and is secured to the trolley 97. The cable 91 extends outwardly from the drum 16 and through a block 100 mounted on the trolley 97, said cable having a weight 101 and a hook 102 at its outer end. The trolley is moved towards the support 96 by reeling in cable 90 on to the drum 13 and allowing the cable 91 to unreel from the drum 16. This is done, as above described, by turning the handle 41 to engage the drum 13 with the friction cone 37 and by turning the handle 46 to disengage the drum 16 from the friction cone 43. At the same time, the differential drive shaft 63 is disengaged from the source of power by the lever 88 and held stationary by the brake 67 operated by the lever 71. The load is lifted from the ground by braking the drum 13 to hold the trolley 97 stationary through the cable 90 and by reeling in cable 91 on to the drum 16 by means of the differential. The drum 16 and the cable 91 might be reeled in by braking the drum 13, disengaging the differential drive shaft from the engine and engaging the drum 16 with the friction cone 43. When the load is clear of the ground, the brake 67 is applied to the differential shaft and the drum 16 is engaged with the friction cone 43 to reel in said drum. The drum 13 will unreel at the same speed as the drum 16 reels in so that the trolley will move towards the support 95.

The sizes of the drums 13 and 16 will vary with the amount of cable wound thereon. If one drum is reeling in its cable faster than the other drum is unreeling its cable, the brake 67 on the differential shaft should be released slightly to allow the one drum to unreel as fast as the other drum is reeling in. On the other hand, if one drum is unreeling its cable faster than the other drum is reeling in its cable, the differential drive shaft should be turned over slowly to reduce the speed of the drum that is unreeling. When the trolley has reached the unloading point, the drum 13 is held stationary by its brake, and the drum 16 is released thus allowing the weight of the load to unreel the latter drum.

Another application of this hoist is illustrated in Figure 7, in which counterbalanced buckets 103 and 104 are to be run to various stations, say, for example, stations 105, 106 and 107 in a shaft 108. With the brake 67 applied to the differential shaft, the bucket 103 is moved to the station 105 by reeling in the drum 13 and the bucket 104 is allowed to drop to the station 107, the weight of said bucket being sufficient to unreel the drum 16. Once the buckets are in this position, they may be operated between the stations 105 and 107 by keeping the brake 67 on and alternately engaging one drum with its friction cone and disengaging the other drum from its friction cone. When it is desired to work between stations 105 and 106, the bucket 103 would be held at station 105 by braking the drum 13 and the drum 16 reeled in by means of the differen-

tial until the bucket 104 reaches the station 105 at which time the buckets may be worked between these stations as described.

Figure 8 illustrates another application of this hoist. In this application, a bucket 110 is to be moved back and forth from one side to the other of a canyon 111. The bucket is lifted off the ground by reeling in both of the drums 13 and 16 and then the brake 67 is applied to the differential shaft. To move the bucket 110 from left to right of Figure 8, the cable 91 is reeled in and the cable 90 is allowed to unreel. When the bucket has reached the desired point, both drums are released and the weight of the bucket causes them to unreel. This procedure is reversed when it is desired to move the bucket 110 from the right to the left of Figure 8.

From the above it will readily be seen that a portable hoist has been provided which is operated by one source of power without loss of power and in which its drums may be counterbalanced one against the other and reeled and unreeled both together and independently of each other by the single source of power.

25. Various modifications may be made in this invention without departing from the spirit thereof or the scope of the claims, and therefore the exact forms shown are to be taken as illustrative only and not in a limiting sense, and it is 30 desired that only such limitations shall be placed thereon as are disclosed in the prior art or are set forth in the accompanying claims.

What I claim as my invention is:

1. In a hoist, a plurality of cable drums, means 35 for selectively connecting said drums to a single source of power, a differential connected to the drums, a drive shaft adapted to connect the differential to the source of power, means for controlling the direction of rotation of the drive 40 shaft, means for connecting and disconnecting the drive shaft and the source of power, means for braking said drive shaft, and means for braking each of the drums, whereby said drums may be counterbalanced against each other and reeled 45 and unreeled both together and independently of each other by the single source of power.

2. In a hoist, a plurality of cable drums, means for selectively connecting said drums to a single source of power, means for selectively braking 50 the drums, a differential connected to the drums, a differential drive shaft, means for connecting and disconnecting the drive shaft and the source of power, means for controlling the direction of rotation of the drive shaft, and a brake on said 55 shaft by means of which the shaft may be held stationary, whereby said drums may be counterbalanced against each other and reeled and unreeled both together and independently of each other by the single source of power.

60. 3. In a hoist, a plurality of cable drums, a spur gear mounted on one end of each, a brake mounted on each drum at the end thereof remote from the spur gear, the spur gear of each drum being adjacent the brake of the other 65 drum, means for selectively connecting the drums to a single source of power, a differential connected to the drums by gears meshing with the spur gears, a differential drive shaft, means for connecting and disconnecting the drive shaft 70 and the source of power, means for controlling the direction of rotation of the drive shaft, and a brake on the shaft by means of which the shaft may be held stationary, whereby said drums may be counterbalanced against each 75 other and reeled and unreeled both together and

independently of each other by the single source of power.

4. In a hoist, a plurality of cable drums, spur gears mounted independently of the drums, a gear meshing with the spur gears, said spur gears being operatively connected to a single source of power means for selectively engaging the drums with the spur gears, a differential adapted to be connected to the same source of power and to the drums, means for connecting and disconnecting the differential and the source of power, and means for braking each drum, whereby said drums may be counterbalanced against each other and reeled and unreeled both together and independently of each other by the single source of power.

5. In a hoist, a plurality of cable drums, spur gears mounted independently of the drums, a gear meshing with the spur gears, said spur gears being rotatably connected to a single source of power, friction cones formed with the spur gears, means for selectively thrusting the drums into engagement with the friction cones to rotate said drums, a differential adapted to be connected to the same source of power and to the drums, means for connecting and disconnecting the differential and the source of power, and means for braking each drum, whereby said drums may be counterbalanced against each other and reeled and unreeled both together and independently of each other by the single source of power.

6. In a hoist, a plurality of cable drums, spur gears mounted independently of the drums, a gear meshing with the spur gears, said spur gears being rotatably connected to a single source of power, friction cones formed with the spur gears, means for selectively thrusting the drums into engagement with the friction cones to rotate said drums, brakes on said drums for selectively holding them stationary, spur gears mounted on the drums, a differential adapted to be connected to the source of power and to the drums by gears meshing with the spur gears thereof, and means for connecting and disconnecting the differential and the source of power, whereby said drums may be counterbalanced against each other and reeled and unreeled both together and independently of each other by the single source of power.

7. In a hoist, a plurality of cable drums, spur gears mounted independently of the drums, a gear meshing with the spur gears, said gears being operatively connected to a single source of power, means for selectively engaging the drums with the spur gears, a differential connected to the drums, a drive shaft adapted to connect the differential to the source of power, means for connecting and disconnecting the drive shaft and the source of power, means for braking said drive shaft, and means for braking each drum, whereby said drums may be counterbalanced against each other and reeled and unreeled both together and independently of each other by the single source of power.

8. In a hoist, a plurality of cable drums, spur gears mounted independently of the drums, a gear meshing with the spur gears, said spur gears being rotatably connected to a single source of power, friction cones formed with the spur gears, means for selectively thrusting the drums into engagement with the friction cones to rotate said drums, means for selectively braking the drums, a differential connected to the drums, a differential drive shaft, means for connecting and disconnecting the drive shaft and the source of power.

power, and a brake on said shaft by means of which the shaft may be held stationary, whereby said drums may be counterbalanced against each other and reeled and unreeled both together and independently of each other by the single source of power.

9. In a hoist, a plurality of cable drums, spur gears mounted independently of the drums, a gear meshing with the spur gears, said spur gears being rotatably connected to a single source of power, friction cones formed with the spur gears, means for selectively thrusting the drums into engagement with the friction cones to rotate the drums, spur gears mounted on the ends of the drums, brakes mounted on the opposite ends of the drums, a differential connected to the drums by gears meshing with the spur gears thereof, a differential drive shaft, means for connecting and disconnecting the drive shaft and the source of power, and a brake on the shaft by means of which said shaft may be held stationary whereby said drums may be counterbalanced against each other and reeled and unreeled both together and independently of each other by the single source of power.

10. In a hoist, a base having side frames, a plurality of cable drums freely mounted on shafts journalled in the side frames, a source of power mounted on the base at the rear of the drums, means for selectively connecting the drums to the source of power, a differential mounted on the base beneath one of the cable drums, said differential being connected to the drums, means for connecting and disconnecting the differential and the source of power, and means for braking the drums, whereby said drums may be counterbalanced against each other and reeled and unreeled both together and independently of each other by the single source of power.

40 11. In a hoist, a base having side frames, a plurality of cable drums freely mounted on shafts journalled in the side frames, friction cones fixedly mounted on the shafts, means for rotatably connecting the friction cones to a single source of power mounted on the base at the rear of the drums, means for selectively thrusting the drums into engagement with the cones to rotate the drums, means for braking the drums, a differential mounted on the base beneath one of the cable drums, means for connecting the differential to the drums, a drive shaft adapted to

connect the differential to the source of power, and means for connecting and disconnecting the drive shaft and the source of power, whereby said drums may be counterbalanced against each other and reeled and unreeled both together and independently of each other by the single source of power.

12. In a hoist, a base having side frames, a plurality of cable drums freely mounted in shafts journalled in the side frames, spur gears fixedly mounted on the shafts, a gear freely mounted on another shaft meshing with the spur gears, means for rotatably connecting the spur gears to a single source of power, friction cones formed with the spur gears, means for selectively thrusting the drums into engagement with the friction cones to rotate the drums, means for selectively braking said drums, a differential mounted on the base beneath one of the cable drums, means for connecting the differential to the drums, a differential drive shaft, means for connecting and disconnecting the shaft and the source of power, and means for braking said shaft, whereby said drums may be counterbalanced against each other and reeled and unreeled both together and independently of each other by the single source of power.

13. In a hoist, a base having side frames, a plurality of cable drums freely mounted on shafts journalled in the side frames, spur gears fixedly mounted on the shafts, a gear freely mounted on another shaft meshing with the spur gears, means for rotatably connecting the spur gears to a single source of power, friction cones formed with the spur gears, means for selectively thrusting the drums into engagement with the friction cones to rotate the drums, spur gears mounted on the ends of the drums, brakes mounted on the opposite ends of the drums, a differential mounted on the base beneath one of the cable drums, gears mounted on shafts extending outwardly from the differential adapted to mesh with the spur gears of the drums, a differential drive shaft, means for connecting and disconnecting the drive shaft and the source of power, a brake on said shaft by means of which said shaft may be held stationary, whereby said drums may be counterbalanced against each other and reeled and unreeled both together and independently of each other by the single source of power.

MICHAEL CULLUM NESBITT.
